DOOR HOLDER

Clifford P. Wicks, Stamford, Conn., assignor to
The Yale & Towne Manufacturing Company,
Stamford, Conn., a corporation of Connecti-
cut

Application March 20, 1936, Serial No. 69,748

2 Claims. (Cl. 292—95)

This invention relates to a device for holding a door in an open position. The art of door holders is a very old one, and even the patented art has been very highly developed, so that there 5 are a great number of patents showing door holders of all types.

My invention comprises an improvement, which, though quite narrow in character, is nevertheless of considerable commercial value and 10 does present quite a forward step.

The commercial development of door holders has been such that the trade has generally accepted the association of a door buffer and a door holding hook as a working combination. To use 15 a hook alone, would permit the door to be injured when opened against the hook or its mounting. The door buffer protects the door from the hook, the hook being available, however, to engage the door and hold it open when desired. A door holding hook and buffer, in the prior art, 20 usually comprises a metal buffer holder in which a resilient buffer is mounted and held, and a door holding hook mounted on an eye formed on the buffer holder.

Since doors are made to open to the right and 25 to the left, it has been customary in this art to mount the eye on which the holding hook is carried, on one side or the other of the buffer, depending on whether or not the buffer is to be used with a right hand or a left hand door. For 30 many years door buffers and holders have been sold in this way; that is, the combination of a buffer and hook, with the hook mounted either on the right or left hand side, and the trade has always ordered left hand or right hand buffers, 35 depending on the direction of opening of the door with which a buffer is to be used.

I have made a radical improvement over the prior art by mounting my hook holding eye on the upper surface of the metal buffer holding 40 portion, so that the hook is now capable of cooperation with either a right or a left hand door. It has been found that when the hook is so mounted, it many times drops into position on the buffer when released from the door and does 45 not drop into a downward position out of the way of the buffer.

I have found that by particularly shaping the upper surface of the buffer, as in the form of an inverted V, the hook when dropped on the 50 buffer will be cammed by this inverted V into a downward side position out of obstructing relation to the buffer. This general combination, including the mounting of the hook and the guiding thereof, I believe, is a very radical improvement in the art, and I shall claim it and the 55

sub-combinations thereof broadly in the claims which are appended hereto.

While I propose to form the inverted V on the metal portion of the buffer, or the buffer holder, it could, of course, be formed on the buffer portion per se, as will be readily appreciated by those skilled in the art. 5

It will probably be helpful now to refer to the accompanying drawing for a description of a particular modification of my invention. In the 10 drawing, Fig. 1 is a view showing a buffer-holder combination, with the holding hook holding the door in open position. Fig. 2 is an end view and section of the buffer and the holding hook, showing the hook as it falls down on the buffer when 15 released from holding position on the door. Fig. 3 illustrates just how the hook is cammed into one of two side positions. 15

Referring now more particularly to the drawing, reference numeral 10 designates the metal 20 portion or buffer holding portion of a buffer held by screws 11 against the floor. It is possible, of course, to use a wall type of buffer in my device. In so far as my invention is concerned, it is immaterial whether the buffer is mounted on the 25 floor or on the wall.

The screw 12 is cast integrally with the portion 10 with its tapered screw portion 12 within an open socket 14, into which a removable resilient 30 buffer body 15 is inserted and preferably rotated so as to be held firmly by the screw portion 13 of the screw 12. 30

An eye 16 is formed on the upper surface of the buffer holder 10 and has mounted thereon a hook 17 which may engage an eye 18 carried by 35 a door 19. It is obvious that in this sort of arrangement, the hook 17 is adapted for cooperation with either a right hand or left hand door, so that it is no longer necessary for buyers of such devices to specify right or left hand devices. 40

In order to prevent the hook from remaining on the upper surface of the buffer body 10 when it is released from the eye 18, the upper surface of the body 10 is formed with an inverted V-portion 20 cooperable with a rounded surface on the hook 17 for camming the hook 17 into its full line or dotted line position, illustrated in Fig. 3. The invention will now probably be quite clear 45 to those skilled in the art.

I now claim:

1. In a combined door buffer and door holder, 50 in which the door holder is a hook carried by means fixed to the door buffer, and the buffer has a rubber buffer portion, means supporting said hook above said rubber buffer portion so that said hook will have a tendency to drop there- 55

on when released from the door, and a V shaped lug on the surface of the buffer directly under said hook for guiding said hook into a downward hanging position in non-obstructing relation to the rubber buffer portion.

5. 2. In a combined door buffer and door holder, in which the door holder is a hook carried by means fixed to the door buffer, and the buffer has a rubber buffer portion, means supporting

said hook above said rubber buffer portion, and a specially shaped upper surface on the buffer for directing gravitational movement of said hook into a downward hanging position in non-obstructing relation to the rubber buffer portion when said hook is released from holding relation to the door. 5
